WINDOW SCREEN SECURING DEVICE

Louis F. Julien, Detroit, Mich., assignor to Chamberlain Metal Weather Strip Company, Inc., Detroit, Mich., a corporation of Michigan

Application June 13, 1938, Serial No. 213,398

12 Claims.

(Cl. 292—19)

This invention relates, in general, to window screens and to means for mounting and securing same in place, and, in particular, to that type of screen used in conjunction with places of detention, such as hospitals, penitentiaries, asylums, and other detention homes.

In the development of the detention type of window screen much thought must be given to the ways and means for preventing its removal from the mounting after its assembly thereon, and to the construction of the screen and its mounting so that the inmate is neither able to dismantle the screen nor to use any of its parts for tools or weapons for causing his escape or injury to himself or others.

With these purposes foremost, one of the objects of this invention is to improve the detention type of window screen so that same cannot be removed by the inmate of the detention home.

Another object of the invention is to improve the construction of the detention type of window screen so that it cannot be raised, lowered, or pried open by the inmate within the room enclosed thereby.

Another object herein is to provide a detention type of window screen with novel means whereby said screen can neither be removed by the inmate nor by anyone else without the use of a specially designed tool which, when properly applied, permits the ready and easy removal of said screen.

Another object of the invention is to provide said specially designed tool by which said detention window is made removable.

Other objects and advantages will become readily apparent from a reference to the following specification taken in conjunction with the accompanying drawings, of which there are three (3) sheets and in which:

Figure 1 is a fragmental front elevation of a window and screen, partly broken away, and showing the invention incorporated therein;

Fig. 2 is a horizontal sectional view of the structure shown in Fig. 1 and taken along the lines 2—2 therein;

Fig. 3 is a vertical end elevational view, in part, of the structure shown in Figs. 1 and 2;

Fig. 4 is a vertical sectional view showing the screen in place and one of the windows in open position;

Fig. 5 is a section taken along the lines 5—5 in Fig. 1;

Fig. 6 is an enlarged perspective view, in part, of the window sash and showing thereon in detail the retaining means for a screen;

Fig. 7 is a plan view of a tool shown in conjunction with a screen and sash, the latter being shown in section, and the tool being in operative position for removing the screen from the sash;

Fig. 8 is a front elevational view of the screen

with the tool, shown in dotted lines, in operative position thereon;

Fig. 9 is a perspective view, broken away, of a portion of the structure shown in Fig. 8;

Fig. 10 is a front elevation of an assembly of window and screens;

Fig. 11 is a fragmental elevational view of a modified form of mounting means shown in Fig. 1, and showing a housing for said mounting means; and

Fig. 12 is a section taken along the lines 12—12 in Fig. 11.

A metal window sash, generally indicated at 10, is shown as being provided with the usual vertical and horizontal frame bars by which are permanently supported the various lights of window glass. The sash 10, for purposes of illustration only, is shown with two ventilation openings 12, each of said openings being formed by a frame 14 and adapted for being closed or opened by an auxiliary sash 16. Pivoted to each side of the frame 14, such as at 18, and to each side of the sash 16, such as at 20, is an arm 22 for permitting swinging motion of sash 16, the sash 16 being provided at each side of its lower edge with a member 24 which is in sliding engagement with a slot 26 in each side of frame 14, whereby the sash 16 is given a compound sliding and swinging movement upon opening or closing thereof.

A screen frame 28, having a panel of wire mesh 30 appropriately secured thereto, is shown as being solid and rectangular in cross section with its members securely joined together, but it is obvious that said frame can assume any shape or construction as long as the purpose thereof will be served. At or near the center of each vertical member of the screen frame 28, on the rear face thereof, there is formed a slot 32 extending from side to side of said member, each of said slots being in horizontal alignment with the other. In the region of each slot 32 there-behind and in a cut-away portion provided therefor in each of said vertical screen frame members there is secured a plate 34, by means of rivets or screws 36, said plates each having a portion extending horizontally outwardly from the frame 28 and provided at its outward end with a forwardly extending flange 38. As will be seen, the slots 32 are made deep enough so as to provide openings through the vertical frame members of the frame 28 after the plates 34 have been secured in place, and that the recesses for the plates 34 are made deep enough so that the rear faces of plate and frame will be substantially flush for affording proper fitting between screen frame and sash frame upon assembly.

For holding the screen frame 28 in place on the frame 14 of opening 12, there is secured on each front vertical facing of the frame 14 a spring

bracket 40, by means of a screw 42, the bracket being formed at its upper end with a clip portion 44 which has an inwardly directed horizontal portion and an outwardly and upwardly directed portion. Between the bracket 40, below its horizontal portion, and the front facing of frame 14, there is secured a pair of plate members 46 and 48 of different heights, plate 48 being the lower as well as the rear plate. The positions of the bracket 40 and the plates 46 and 48 are such that, when the screen frame 28 is assembled on to the frame 14, the outwardly projecting portion of each plate 34 on the frame 28 can be snapped downwardly past the clip portion 44 of each bracket 40 and rest on top of its respective plate 48, the flange 38 of each plate 34 just clearing the outer edge of the bracket 40 so as to hold the frame 28 against side-to-side movement, the assembly being such as to hold the screen frame 28 in flush engagement with the frame 14 for opening 12. It will be noted in Figs. 6 and 7 that the edge of the clip portion 44 of bracket 40 adjacent the opening 12 is inwardly cut, such as at 50, the purpose of which being later explained. The horizontal portion of the clip 44 of bracket 40 prevents upward displacement of the screen frame 28 from the frame 14, and the flanges 38 prevent distortion of the frame 28 which would result if the frame 28 were pushed outwardly from within or if a sharp wedging tool were applied from within between the frames 14 and 28. It is obvious that the above explained retaining structures for the screen frame can be supplied in greater numbers than as shown, one per side, but it is not necessary to use more than that number. If the size of the screen frame calls for support at more than one place per side, the additional support can comprise a simple outwardly extending lug on the screen frame which engages one leg of a springless Z-shaped bracket the other leg of which being secured to the frame 14. Such a simple structure would prevent outward and downward movement of the screen frame at that point.

In order to effect the removal of the screen frame 28 from the frame 14 when the operator is in the detention room, there is provided a collapsible tool, generally indicated at 52, said tool comprising a pair of relatively movable arms 54 slidable within a pair of collars 56, and a pair of handle members 58. One of the collars 56 is provided with a set screw 60 by means of which the distance between the outer ends of arms 54 can be adjusted and maintained. The outer end of each arm 54 is beveled, such as at 62, to provide thereat a substantial knife edge, each of said ends being adapted, when the arms 54 of tool 52 are extended, to fit into and extend through one of the slots 32 in the screen frame 28, the knife edge 62 engaging the cut-in portion 50 of the spring bracket 40 and forcing the latter forwardly away from the top of the outwardly extending portion of the plate 34 on the frame 28 and permitting said frame 28 to be slid upwardly away from the bracket 40. Since each of the arms 54 of the tool 52 is now in its respective slot 32 which is walled in at the rear by the plate 34, and since the arms 54 have been presumably locked together in their extended positions by the screw 60, the screen 28 can be then maneuvered into the room by the handles 58 on tool 52.

In Figs. 11 and 12, there are shown the above described cooperative retaining structures for the frames 14 and 28 together with a housing 64

which is secured to the frame 28 by the rivets or screws 36 and which encloses against the weather and manual tampering said retaining structures, the housing being open at the bottom only so that the screen can be removed in the above described manner. Provision of this housing 64 necessitates the use of tool 52 in any case of removal or installation of the screen frame 28, whether from inside or outside the detention room.

Although the invention has been described with some detail, the description is not intended to limit the scope of the inventive idea. The right is reserved to make such changes in the details of construction and arrangement of parts as will come within the purview of the attached claims.

What I claim is:

1. A device for locking a closure member in place over an opening in a wall and comprising, a pair of clamp supports fixed to the wall adjacent and at opposite sides of the opening therein, an arm for and to be lockingly supported by each of said supports and spacedly fixed to the member in accordance with the spacing between said supports, and a restricted opening between the member and each of said arms for providing communication between the inner and outer sides of the member wherethrough a tool is insertable for releasing said arms from said supports.

2. A device for locking a closure member in place over an opening in a wall and comprising, a pair of supports fixed to the wall adjacent to and on opposite sides of the opening therein, each of said supports including an abutment member and a clamping member, each of said clamping members being normally engageable with the wall at a spaced distance from its respective abutment member and having a portion arranged perpendicularly to the wall, and a pair of arms fixed to the closure member and operable for abutting engagement with said abutment members in opposed relation to said perpendicular portions of said clamping members whereby movement of the closure member from said abutment members past said perpendicular portions is positively prevented.

3. A device for locking a closure member in place over an opening in a wall and comprising, a pair of supports fixed to the wall adjacent to and on opposite sides of the opening therein, each of said supports including an abutment member and a clamping member, each of said clamping members being normally engageable with the wall at a spaced distance from its respective abutment member and having a portion arranged perpendicularly to the wall, a pair of arms fixed to the closure member and operable for abutting engagement with said abutment members in opposed relation to said perpendicular portions of said clamping members whereby movement of the closure member from said abutment members past said perpendicular portions is positively prevented, and a cover for each of said supports and said arm supported thereby for rendering same inaccessible.

4. A device for locking a closure member in place over an opening in a wall and comprising, a pair of supports fixed to the wall adjacent to and on opposite sides of the opening therein, each of said supports including an abutment member and a clamping member, each of said clamping members being normally engageable with the wall at a spaced distance from its respective abutment member and having a portion arranged perpendicularly to the wall, a pair of arms fixed

to the closure member and operable for abutting engagement with said abutment members in opposed relation to said perpendicular portions of said clamping members whereby movement of the closure member from said abutment members past said perpendicular portions is positively prevented, and a restricted opening through the closure member adjacent the position of each of said clamping members through which a tool is inserted for releasing said clamping members from said arms.

5. A device for locking a closure member in place over an opening in a wall and comprising, a pair of clamp supports fixed to the wall adjacent and at opposite sides of the opening therein, each of said supports having a cam surface, an arm for and to be lockingly supported by each of said supports and spacedly fixed to the member in accordance with the spacing between said supports, and a restricted opening between the member and each of said arms for providing communication between the inner and outer sides of the member wherethrough a tool is insertable for engaging said cam surfaces and releasing said arms from said supports.

6. A device for locking a closure member in place over an opening in a wall and comprising, a pair of supports fixed to the wall adjacent to and on opposite sides of the opening therein, each of said supports including an abutment member and a clamping member, each of said clamping members being normally engageable with the wall at a spaced distance from its respective abutment member and having a portion arranged perpendicularly to the wall, each of said clamping members also having a cam surface, a pair of arms fixed to the closure member and operable for abutting engagement with said abutment members in opposed relation to said perpendicular portions of said clamping members whereby movement of the closure member from said abutment members past said perpendicular portions is positively prevented, and a restricted opening through the closure member adjacent the position of each of said clamping members through which a tool is inserted for engaging said cam surfaces and releasing said clamping members from said arms.

7. A device for locking a closure member in place over an opening in a wall and comprising, a clamp support fixed to the wall adjacent the opening therein, an arm for and to be lockingly supported by said support and fixedly positioned onto the member in accordance with the positioning of said support, and a restricted opening between the member and said arm for preventing communication between the inner and outer sides of the member wherethrough a tool is insertable for releasing said arm from said support.

8. A device for locking a closure member in place over an opening in a wall and comprising, a support fixed to the wall adjacent the opening therein, said support including an abutment member and a clamping member, said clamping member being normally engageable with the wall at a spaced distance from said abutment member and having a portion arranged perpendicularly to the wall, and an arm fixed to the closure member and operable for abutting engagement with said abutment member in opposed relation to said perpendicular portion of said clamping member whereby movement of the closure member from said abutment member past said perpendicular portion is positively prevented,

9. A device for locking a closure member in place over an opening in a wall and comprising, a support fixed to the wall adjacent the opening therein, said support including an abutment member and a clamping member, said clamping member being normally engageable with the wall at a spaced distance from said abutment member and having a portion arranged perpendicularly to the wall, an arm fixed to the closure member and operable for abutting engagement with said abutment member in opposed relation to said perpendicular portion of said clamping member whereby movement of the closure member from said abutment member past said perpendicular portion is positively prevented, and a cover for said support and said arm supported thereby for rendering same inaccessible.

10. A device for locking a closure member in place over an opening in a wall and comprising, a support fixed to the wall adjacent the opening therein, said support including an abutment member and a clamping member, said clamping member being normally engageable with the wall at a spaced distance from said abutment member and having a portion arranged perpendicularly to the wall, an arm fixed to the closure member and operable for abutting engagement with said abutment member in opposed relation to said perpendicular portion of said clamping member whereby movement of the closure member from said abutment member past said perpendicular portion is positively prevented, and a restricted opening through the closure member adjacent the position of said clamping member through which a tool is inserted for releasing said clamping member from said arm.

11. A device for locking a closure member in place over an opening in a wall and comprising, a clamp support fixed to the wall adjacent the opening therein, said support having a cam surface, an arm for and to be lockingly supported by said support and fixedly positioned onto the member in accordance with the positioning of said support, and a restricted opening between the member and said arm for preventing communication between the inner and outer sides of the member wherethrough a tool is insertable for engaging said cam surface and releasing said arm from said support.

12. A device for locking a closure member in place over an opening in a wall and comprising, a support fixed to the wall adjacent the opening therein, said support including an abutment member and a clamping member, said clamping member being normally engageable with the wall at a spaced distance from said abutment member and having a portion arranged perpendicularly to the wall, said clamping member also having a cam surface, an arm fixed to the closure member and operable for abutting engagement with said abutment member in opposed relation to said perpendicular portion of said clamping member whereby movement of the closure member from said abutment member past said perpendicular portion is positively prevented, and a restricted opening through the closure member adjacent the position of said clamping member through which a tool is inserted for engaging said cam surface and releasing said clamping member from said arm.

LOUIS F. JULIEN,
